(57) **CLAIM**

The ornamental design for a garden hose, as shown and described.

DESCRIPTION

FIG. 1 is a partial perspective view of the garden hose in a retracted position in accordance with the present invention; FIG. 2 is a partial right side view of a section of the garden hose taken along line 2-2 of FIG. 1 with the garden hose being in a partial extended position, it being understood that the left side view is a mirror image therefrom; and, FIG. 3 is a partial right side view of a section of the garden hose taken along line 3-3 of FIG. 1 with the garden hose stretched taut, it being understood that the left side view is a mirror image therefrom.

The section lines and numbering shown on FIG. 1 indicate the locations of partial sections from which FIGS. 2 and 3 are taken and form no part of the claimed design.

The elements of the garden hose depicted in the various figures are boundary lines and form no part of the claimed invention.
